(57) **CLAIM**

The ornamental design for a connector housing for an electrical connector, as shown and described.

DESCRIPTION

FIG. 1 is a top, front and left side perspective view of a connector housing shown in a state of use;

FIG. 2 is a top, back and left side perspective view of the connector housing of FIG. 1;

FIG. 3 is a bottom, back and right side perspective view of the connector housing of FIG. 1;

FIG. 4 is a front view of the connector housing of FIG. 1;

FIG. 5 is a back view of the connector housing of FIG. 1;

FIG. 6 is a left side view of the connector housing of FIG. 1;

FIG. 7 is a right side view of the connector housing of FIG. 1;

FIG. 8 is a top view of the connector housing of FIG. 1; and, FIG. 9 is a bottom view of the connector housing of FIG. 1. The broken lines in the drawings are for the purpose of illustrating environmental subject matter and portions of the article which form no part of the claimed design.

1 Claim, 3 Drawing Sheets
